UNITED STATES PATENT OFFICE

DORA S. MILLER, OF LOS ANGELES, CALIFORNIA

DESIGN FOR AN AUTO PURSE

Application filed October 28, 1930. Serial No. 37,410. Term of patent 3½ years.

To all whom it may concern:

Be it known that I, DORA S. MILLER, a citizen of the United States, residing at 5006 Melrose Avenue, Los Angeles, in the county of Los Angeles and State of California, have invented a new, original, and ornamental Design for Auto Purse, of which the following is a specification, reference being had to the accompanying drawings, forming part thereof.

Fig. 1 is a side elevational view of an auto purse showing my new design.

Fig. 2 is a rear elevational view.

I claim:

The ornamental design for an auto purse, as shown.

DORA S. MILLER.
